(57) **CLAIM**

I claim the ornamental design for a “drift and strike indicator for fishing,” as shown.

DESCRIPTION

FIG. 1 is a perspective view of the drift and strike indicator for fishing;

FIG. 2 is a front view of the drift and strike indicator for fishing of FIG. 1;

FIG. 3 is a rear view of the drift and strike indicator for fishing of FIG. 1;

FIG. 4 is a left side view of the drift and strike indicator for fishing of FIG. 1;

FIG. 5 is a right side view of the drift and strike indicator for fishing of FIG. 1;

FIG. 6 is a top view of the drift and strike indicator for fishing of FIG. 1;

FIG. 7 is a bottom view of the drift and strike indicator for fishing of FIG. 1;

FIG. 8 is a perspective view of the drift and strike indicator for fishing of FIG. 1;

FIG. 9 is a flow diagram of applying the drift and strike indicator for fishing of FIG. 1 to a leader; and,

FIG. 10 is an environmental view of the fly fishing strike indicator of FIG. 1 in use.

Broken lines depict portions of the drift and strike indicator for fishing, illustrate environmental features, and form no part of the claimed design.

The nature and intended use of the article in which the design is embodied is for fly fishing.
